UNITED STATES PATENT OFFICE.

GEORGE S. LEWIS, OF CHICAGO, ILLINOIS.

SPRING-POST FOR BICYCLE SEATS OR HANDLE-BARS.

SPECIFICATION forming part of Letters Patent No. 699,400, dated May 6, 1902.

Application filed December 9, 1901. Serial No. 85,180. (No model.)

To all whom it may concern:

Be it known that I, GEORGE S. LEWIS, a citizen of the United States, residing at Chicago, in the county of Cook and State of Illinois, have invented certain new and useful Improvements in Spring-Posts for Bicycle Seats or Handle-Bars, of which the following is a specification.

This invention relates particularly to spring seat-posts for bicycles, although equally well adapted to spring-posts for handle-bars. As now constructed the two principal forms of these devices are known as "plain" spring seat-posts and spring seat-posts with internal expanders. Owing to its construction, the plain spring seat-post usually requires an outside expander separate and distinct from the post itself to fasten the same to the bicycle or the opening therefor in the bicycle or motorcy-
cle adapted to receive the post must be made in some form of open ring to be closed by a seat-post bolt, which ring may be a part of the bicycle or motorcycle itself. Spring seat-posts with internal expanders as now constructed are objectionable on account of multiplicity of parts, excessive length, special wrench or tool required for adjustment; the necessity for taking apart while adjusting to the bicycle, and the extra cost of manufacture, owing to the construction and number of parts.

At the present time bicycles and motorcycles are almost universally made with what is known as a "solid cluster" at the seat-post, which practically necessitates the use of some form of internal expander to fasten the post.

The object of my invention is therefore the construction of a spring-post provided with an internal expander which will be comparatively free from the objections and disadvantages to which present forms of spring-posts with internal expander are subject.

In a general way my invention consists in a spring-post having an internal expander-plug and provided with a coupling-rod to limit the distance of longitudinal expansion of said post, which rod serves also to control the movement of said expander-plug and is provided with means for increasing or diminishing its own length as a coupler to vary the resiliency of the spring; and my invention further consists in the various details of construction and in combinations of parts, all as

hereinafter described, and particularly pointed out in the claims.

My invention will be more readily understood by reference to the accompanying drawings, forming a part of the specification, and in which—

Figure 1 is a vertical central longitudinal section of a complete device embodying my invention. Fig. 2 is a bottom plan of the same. Fig. 3 is a horizontal section substantially on the line $x-x$ of Fig. 1. Figs. 4 and 5 are details subsequently described.

Referring now to the drawings in detail, numeral 2 refers to a tube of proper gage for insertion in the seat-post mast provided with the slots 3 3 at the lower extremity thereof, to permit of the expansion of the tube at this end by means of the expander-plug 4 to grip 70 said seat-post mast. Telescoping within said tube 2 is the tube 5, which forms a part of the seat-post proper, preferably of the usual L construction. Extending longitudinally through the telescoping tubes 2 and 5 is the bolt-rod 6, having a permanent head 7 and threaded at its lower extremity to receive the nut 8. This bolt-rod 6 is preferably circular in cross-section throughout the greater portion of its length, the portion 9, however, being rectangular in cross-section for reasons which will subsequently appear. The lower extremity of the tube 5 is provided with longitudinally-extending slots 10 10, designed, in connection with the lugs 11 11 on the interior of the tube 85 2, to prevent rotation of the tubes 2 and 5 with reference to each other.

Threaded longitudinally through the expander-plug 4 is the screw 12, having a head 13 slightly less in diameter than the inside 90 diameter of the tube 2. Said head 13 is provided with the notches 14 14 to permit of the withdrawal of said screw past the lugs 11 11. Said screw 12 is further provided with a central bore extending longitudinally through 95 the same, at least a part of which is rectangular in cross-section, designed to fit the rectangular portion 9 of said bolt-rod 6 to effect the joint rotation of both screw and bolt-rod. A flange 15, suitably mounted on the interior 100 wall of the tube 2, in connection with the head 13 above and the washer 16 and the nut 17 below, prevents vertical movement of said screw 12 within said tube. Said screw 12 being pro-

vided with one or more flattened sides and the washer 16 being flat-faced to conform thereto, said washer and nut will rotate with said screw, retaining the same relative position.

5 Said nut 17 is preferably operable by means of a U-shaped wire wrench and the holes 18 18, oppositely located in said nut 17.

Surrounding the bolt-rod 6 within the telescoping tubes is the spring 19, compressed between the head of the tube 5 and the screw-head 13. This spring provides the resiliency of said post and may be of usual pattern, size, and strength, its function being too well known to require further description. The 15 bolt-rod 6 limits the combined length of said telescoping tubes, holding them under action of said spring. It is evident that by means of the nut 8 and the threaded extremity 21 the length of said post, and consequently the 20 compression of said spring, may be increased or diminished. A plurality of washers 20 20 may be provided at the lower extremity of said bolt-rod 6 to bring the nut 8 within easy access. In assembling the parts which make 25 up my complete device the washer 16 and the nut 17 are of course properly placed prior to the insertion of the expander-plug 4.

It will be apparent that the bolt-rod 6 is adapted to serve three separate and distinct 30 functions. In the first place it acts as a coupler between the two telescoping tubes, thereby limiting the extent of longitudinal expansion of said post; secondly, rotation of said bolt-rod 6 will rotate said screw and operate 35 to move the expander-plug 4 up or down, thereby tightening or loosening the seat-post in the seat-post mast; thirdly, by means of the threaded extremity 21 and the nut 8 the compression of said spring may be changed to 40 give greater or less resiliency to said post, as may be desired. It is obvious, furthermore, that while I have largely confined my description to a spring seat-post my invention is 45 equally well adapted to be used as a spring-post for handle-bars.

Many modifications of the details of my improved spring-post may also suggest themselves to those skilled in the art to which it appertains, and I therefore do not desire to 50 limit my invention to the specific construction herein shown and described.

Having thus described my invention, I claim as new and desire to secure by Letters Patent—

55 1. In a spring-post for bicycles, the combination with a longitudinally-resilient, tubular post, of a coupling-rod limiting the longitudinal expansion of said post, an internal expander-plug, a screw threaded therein to raise 60 and lower said plug, means for operating said screw by rotation of said coupling-rod, and means for limiting the movement of said screw to that of rotation only.

65 2. In a spring-post for bicycles, the combination with a longitudinally-resilient, tubular post, of a coupling-rod therein to limit the distance of longitudinal expansion, an ex-

pander-plug, a screw threaded therein to raise and lower said plug, external means for rotating said rod, connecting means between 70 said rod and screw to rotate said screw, and means for limiting the movement of said screw to that of rotation only.

3. In a spring-post for bicycles, the combination with a longitudinally-resilient, tubular post, of a coupling-rod limiting the longitudinal expansion of said post, an expander-plug, a screw threaded therein to operate said plug, external means for rotating said coupling-rod, connecting means between said rod 75 and screw to rotate said screw, means for limiting the movement of said screw to that of rotation only, and means for varying the resiliency of said spring.

4. In a spring-post for bicycles, the combination with a longitudinally-resilient, tubular post, of a coupling-rod limiting the longitudinal expansion of said post, a screw-controlled, expander-plug operable by rotation of said coupling-rod, and connecting means between 80 90 said rod and spring to increase or diminish the distance of expansion of said post.

5. In a spring-post for bicycles, the combination with a longitudinally-resilient, tubular post, of a screw-controlled, internal expander-plug, a coupling-rod limiting the longitudinal expansion of said post, connecting means between 95 said screw and rod to operate said screw by rotation of said rod, and means for varying the length of said coupler to increase 100 or diminish the resiliency of said spring.

6. In a spring-post for bicycles, the combination with a longitudinally-resilient, tubular post, of a coupling-rod limiting the longitudinal expansion of said post, an expander-plug, a screw threaded therein to operate 105 said plug, external means for rotating said coupling-rod, connecting means between said rod and screw to rotate said screw, means for limiting the movement of said screw to that 110 of rotation only, and means for varying the length of said coupler to increase or diminish the resiliency of said spring.

7. In a spring-post for bicycles, the combination with a longitudinally-resilient, tubular 115 post of internal expander-plug, means for preventing rotation of said plug, a screw threaded therein to raise and lower said plug, means for limiting the movement of said screw to that of rotation only, a coupling-rod 120 limiting the longitudinal expansion of said post, said rod being freely slideable longitudinally through said screw and rotatable to operate said screw, and means for varying the length of said coupling-rod.

In testimony of the foregoing I have hereunto set my hand, this 3d day of December, 1901, in the presence of two subscribing witnesses.

GEORGE S. LEWIS.
